UNITED STATES PATENT OFFICE.

WILLIAM S. COOPER, OF PHILADELPHIA, PENNSYLVANIA.

VALVE FOR WATER-CLOSETS.

SPECIFICATION forming part of Letters Patent No. 371,431, dated October 11, 1887.

Application filed December 30, 1886. Serial No. 222,965. (No model.)

To all whom it may concern:

Be it known that I, WILLIAM S. COOPER, a citizen of the United States, residing in Philadelphia, Pennsylvania, have invented certain 5 Improvements in Valves for Water-Closets, of which the following is a specification.

My invention consists of certain improvements in the construction of valves for the supply of water to water closets which have a 10 siphon-discharge, or are so thoroughly flushed as to clear out the sealing-traps or standing water-pools of the closet, the main object of my invention being to so construct the valve as to insure the proper filling of the traps or pools 15 after the siphon or flushing action has ceased.

In the accompanying drawings, Figure 1 is a longitudinal section, partly in elevation, of a water-closet valve constructed in accordance with my invention, the valve being shown in 20 the open position; and Figs. 2 and 3 are sections of part of the valve, showing the action as the valve is being closed.

In Fig. 1, A represents the discharge-easing of the valve, which is secured to the casing A' 25 of the tank in any suitable manner, and contains an internal bucket, B, between which and the outer casing is a passage, x, of sufficient area for the flow of water when the valve is fully opened.

The valve D has a packing-ring, a, which is 30 adapted to a seat, y, around the inlet-opening or mouth of the casing A, and cuts off the flow of water when the valve is lowered to said seat, and the valve has a tubular stem, b, which 35 is fitted loosely to a guide-pin, d, in the bucket B, and carries at its lower end a plunger, F, having a loose packing-ring, f, confined between upper and lower flanges, i i', of the plunger. This ring offers no obstacle to the 40 free rise of the plunger, as the ring during this movement rests on the lower flange, i', so that water can pass freely around the upper flange, i, and over the ring into the bucket B; but as soon as the plunger commences to descend the 45 ring is caused to bear against the beveled under face of the upper flange, i, whereby the ring is forced outward against the side of the bucket, and the escape of water around said upper flange is prevented. The water trapped 50 in the lower portion of the bucket is thus caused to pass upward between the pin d and

stem b of the valve and escapes through an opening, m, in the hub g of said valve, the area of this opening determining the rate of speed at which the valve is permitted to close 55 to its seat after having been elevated and then released. A perforated plate, n, at the upper end of the hollow stem b, serves to prevent the access to the opening m of particles so large as to have any tendency to clog said opening, so 60 that interference with the operation of the valve, due to this cause, is prevented.

When the valve is fully opened, as in Fig. 1, free flow of water into the closet is permitted, a large volume of water thus entering the 65 closet and causing the siphon or flushing action in the discharge-pipe of the same. This siphon or flushing action draws all the water from the bowl and traps or pools of the discharge-pipe; hence it is important that after 70 the action has ceased there should be a flow of water into the closet sufficient in volume to insure the proper filling of all the traps or pools. This object I effect by providing the valve with a downwardly-projecting flange, s, 75 the lift of the valve being such that the bottom of said flange is raised above the seat y to a sufficient extent to insure the desired free flow of water to the closet in the first instance for siphoning or flushing purposes. As the 80 valve descends, the flange enters the mouth of the discharge-easing a; but as the external diameter of the lower portion of the flange is slightly less than the internal diameter of the mouth a restricted flow of water to the closet 85 is permitted, as shown in Fig. 2, this flow being somewhat increased in volume as the valve approaches the limit of its downward movement, owing to the fact that the flange s is 90 slightly contracted in diameter at and near its upper end. (See Fig. 3.)

Although I prefer to form the escape-opening m in the hub of the valve, as shown, on account of the simplicity and cheapness of this construction and the comparative inaccessibility of the opening to foreign particles tending to clog it, other means of regulating the discharge from the bucket on the descent of the plunger may be used in carrying out my invention. For instance, the plan shown in my 95 application filed March 31, 1884, No. 126,132, or that shown in my application filed July 26,

1886, No. 209,090, may be adopted for the purpose, or other known means of restricting the speed of movement of the valve in closing may be used.

5 I claim as my invention—

1. The combination, in a water-closet-supply valve, of a discharge chest, a valve constructed to close the mouth of the chest and having a depending flange or projection somewhat less in size than the said mouth, and means for raising the valve so that the lower end of the flange is above the top of the mouth, whereby when the valve is first opened a full flow of water through the chest is permitted, 15 which flow is diminished when in the closing movement of the valve the flange of the same enters the mouth of the discharge chest, the diminished flow continuing during the remainder of the movement, all substantially as specified.
2. The combination, in a water closet-supply valve, of a discharge-chest, a valve constructed to close the mouth of the chest, and having a depending flange less in size than 20 said mouth, but constructed to enter the same and restrict the flow as the valve commences to close, and means, substantially as described, for retarding the closing movement of the valve, all substantially as specified.

3. The combination of the discharge-chest 30 and the controlling-valve having a tapered flange adapted to enter the mouth of the chest as the valve closes, said tapered flange bearing such relation to the mouth of the chest that after the main flow of water is cut off 35 there will be a supplementary flow of limited but increasing volume, all substantially as specified.

4. The combination of the discharge-chest and its trapping-bucket with the valve having 40 a hollow stem with plunger at the lower end and contracted discharge-opening at the upper end, all substantially as specified.

5. The combination of the discharge-chest and its trapping-bucket, the valve having a 45 hollow stem with plunger at the lower end and discharge opening at the upper end, and the perforated plate beneath the discharge-opening, all substantially as specified.

In testimony whereof I have signed my name 50 to this specification in the presence of two subscribing witnesses.

WILLIAM S. COOPER.
